UNITED STATES PATENT OFFICE.

ROY M. RICKERT, OF DENVER, COLORADO, ASSIGNOR OF ONE-HALF TO FRANK D. SANDY, OF DENVER, COLORADO.

AMUSEMENT-TICKET MACHINE.

1,026,605.

Specification of Letters Patent.

Patented May 14, 1912.

Application filed October 31, 1911. Serial No. 657,904.

To all whom it may concern:

Be it known that I, ROY M. RICKERT, a citizen of the United States, residing in the city and county of Denver and State of Colorado, have invented certain new and useful Improvements in Amusement - Ticket Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in machines for supplying tickets, more especially adapted for use in connection with places of amusement, and embodies mechanism whereby these tickets are printed, perforated and delivered, either singly or in series, consisting of a strip containing a plurality of tickets.

My improved machine is equipped with a number of operating levers, each lever having its exposed extremity provided with a sort of push-button upon which is formed a number or character indicating the number of connected tickets to be delivered. These keys or levers, as illustrated in the drawing, are five in number, their ends or push-button extremities being numbered from one to five. When any lever is actuated, a drum is moved downwardly, and a gear with which it is equipped is caused to mesh with an operating gear and also with a gear connected with a printing roll, whereby the drum is rotated, and, in turn, imparts rotary movement to the said roll. The depressed lever interlocks with retaining levers, which are arranged to be released by lugs formed upon the said drum, these lugs being so located that the drum is maintained in operative connection with the operating gear and the gear of the printing roll for a longer or shorter time, as may be desired, and according to the position of the operated lever.

As illustrated in the drawing, where there are five levers, there are five of the lugs for actuating the retaining levers, one of these lugs being arranged to release its retaining lever when the drum has made approximately one-fifth of a rotation, whereby the paper web, which supplies the tickets, is only drawn far enough in contact with the

printing roll to print a single ticket, and as soon as this occurs, the interlocked levers are disengaged and the drum moves upwardly in response to the recoil action of a spring which supports the frame in which the drum is journaled. At the same time, a coil spring, located within the drum, acts to return the drum to its normal position. Simultaneously with the upward movement of the drum, a knife is actuated whereby the ticket is cut off. If the lever containing the number 5, for instance, is actuated, the drum will be held in the depressed position, and, consequently, in operative connection with the operating gear and the gear of the ticket printing roll long enough to print five tickets before the interlocked levers are released and the ticket strip cut off.

Provision is made for automatically perforating the paper web between each two tickets, whereby the individual tickets may be readily separated from a strip containing a series, if desired.

As illustrated in the drawing, my improved machine is operated by an electric motor, which may be constantly in motion while the sale of tickets is going on, whereby the operating gears are at all times ready to operate the drum, whenever the latter is depressed sufficiently to form an operative connection with the operating gears.

Having briefly outlined my improved construction, I will proceed to describe the same in detail, reference being made to the accompanying drawing, in which is illustrated an embodiment thereof.

In this drawing: Figure 1 is a side elevation of the machine, a portion of the removable plate or door and also the inner wall of the casing being partly broken away. Fig. 2 is a section, taken on the line 2-2 of Fig. 1, looking forwardly or in the direction of the arrow. Fig. 3 is a section, taken on the line 3-3 of Fig. 2, looking toward the right. Fig. 4 is a section taken on the line 4-4 of Fig. 2. Fig. 5 is a section, taken through the coöperating ticket printing and perforating rolls. This is a section taken on the line 5-5 of Fig. 6. Fig. 6 is a section taken through the printing and perforating rolls on a plane coincident with the longitudinal axes of the rolls. Fig. 7 is a top plan view of the machine with the top plate of the casing partly broken

away to disclose the mechanism within. Fig. 8 is a section, taken on the line 8-8 of Fig. 2, the upper part of the machine being broken away.

5 The same reference characters indicate the same parts in all of the views.

Let the numeral 5 designate an outer casing, which slopes downwardly in front, as shown at 6, and is provided with openings 7 through which the forward extremities 8 of key levers 9 protrude, the said levers having their inner extremities pivotally connected with a spindle 10, located within the casing and supported by parallel plates 12 and 13, the levers being spaced on the said spindle by separating sleeves 14. The outer extremities of these levers are equipped with buttons 15 upon which are formed numerals from one to five,—see Fig. 7. Of course, the 10 number of levers may be as great as desired, depending only upon the size of the machine. Each of these levers is normally held at its upward limit of movement by a spiral spring 16, one extremity of which is connected with a rod 17, supported by the plates 12 and 13; while the other extremity of the 15 spring is connected with the lever, as shown at 18.

Above the lever and located about mid-way between its extremities is a stop rod 19, surrounded by a sleeve 20 for limiting the upward movement of the lever, under the influence of the spring 16. Each lever 9 is provided with a depending arm 21, whose lower extremity is formed into a hook-shaped head 22, having a curved face 23 and an offset 24, these parts being arranged, when the lever is depressed, to engage and interlock with the correspondingly shaped upper extremity 25 of a retaining lever 26, which is fulcrumed intermediate its extremities on a rod 27, its lower extremity being connected, as shown at 28, with one end of a coiled spring 29, the opposite end of the 20 spring being secured to the bottom of the casing, as shown at 30. Each of these levers 26 is arranged in front of and in close proximity to a revolving drum 31, which is journaled on a spindle 32 with which one extremity of a coiled spring 33, located within the drum, is connected, as shown at 34, while the outer extremity of the said spring is connected with the inner surface of the drum, as shown at 35. This spring, normally holds the drum in a certain predetermined position, this position being further determined by a locking dog 36, pivotally mounted, as shown at 37, on a U-shaped member 38, pivotally connected with a rod 39 mounted in the plates 12 and 13, the said dog having a hook-shaped extremity 40 constructed to automatically interlock with a tooth 3 formed on one extremity of the drum. This dog is held in position to interlock with the tooth of the drum by a coiled 45

spring 98 connected with the dog at one extremity, as shown at 99, and at its opposite extremity with the lower end 100 of a depending member 101 connected with the U-shaped frame-plate 38, as shown at 102. This dog 36 prevents the drum from moving beyond its normal position under the recoil action of its spring. The U-shaped frame member 38 is riveted, as shown at 40, to two vertically disposed U-shaped frame members 41 and 42, the U-shaped frame member 38 being horizontally disposed. The frame members 41 and 42 are rigidly secured to the frame member 38, and therefore, move with the latter. The depending arm 21 of each key lever 9 passes through an opening 43 formed in the top of the frame member 41, while the upper extremity of the lever 26 protrudes through an opening 44 formed in the top of the frame member 42. The openings 43 and 44 in the two frame members are sufficiently large, as not to interfere with the levers 9 and 26 during the vertical movement of the drum 31, and the frame upon which it is mounted.

A coil spring 45 is connected at one extremity of the U-shaped frame member 38, as shown at 46, while its opposite extremity is connected with a rod 47 supported at the upper extremity of the two frame plates 12 and 13. This spring is placed under tension by the downward movement of the drum and its oscillatory frame, composed of the members 38, 41 and 42, and, consequently, as soon as the drum acts upon the lever 26, whereby the interlocking connection between the said lever and the arm 21 of the lever 9 is broken, the spring 45 returns the oscillatory frame and the drum to their upward limit of movement.

As illustrated in the drawing, the drum 31, as well as the other rotary elements of the mechanism, is operated from a motor 48, whose operating shaft 49 is equipped with a worm 50 engaging the toothed periphery 51 of a worm wheel 52, fast on a spindle 53, journaled in the stationary frame plates 12 and 13. Upon the spindle 53 is made fast a gear wheel 54, which meshes with a gear 55 mounted on a spindle 56, the last-named gear meshing with a gear 57 mounted on the spindle 27. This gear 57 is in position to mesh with a gear 59 mounted on one end of the drum 31, when the drum is depressed by the downward movement of a key lever, whereby the depending arm 21 of the lever is caused to interlock with the hook-shaped extremity of a retaining lever 26. The drum, when so actuated, moves in the direction indicated by the arrow in Fig. 3. Fast on a spindle 60 is a printing roll 61, the said spindle being journaled in the lower portion of a stationary frame plate 13 at one extremity, and in a relatively short frame plate 62 at the opposite extremity, the last-

named frame plate being interposed between the frame plate 13 and a removable door plate 63 secured to the outer wall of the casing 5 on one side of the machine by means of thumb-screws 64. Fast on the inner extremity of the spindle 60 is a gear 65 arranged to mesh with the gear 59 of the drum when the latter is depressed to cause its gear to mesh with the operating gear 57, as heretofore explained. Hence, as soon as the drum begins to rotate, the printing roll 61 also begins to rotate in the direction indicated by the arrow adjacent said roll in Fig. 3. The gear 65 meshes with a similar gear 66 fast on a spindle 67 to which is also secured a perforating roll 68, coöperating with the printing roll to draw a paper web 69, of light cardboard, from a spool 70, journaled between plates 71 projecting upwardly from the top of the main casing 5, the lower extremities of the said plates being secured to the main casing by screws 72.

The parallel spool-carrying plates 71 are vertically slotted, as shown at 73, to receive projections 74 formed on a block of metal 75, which rests upon the periphery or outer surface of the paper web roll 76 and serves as a tension device to cause the paper web to be evenly unwound from the roll during the operation of the machine, and preventing the momentum of the roll from serving to unwind the paper web after the power, acting to feed the paper web, has ceased to act. The paper web passes downwardly from the roll through an opening formed in the upper part of the casing and passes underneath a guide roller 77 mounted in the casing, whence it passes rearwardly in a horizontal plane approximately between the printing and perforating rolls 61 and 68. Each half rotation of a printing and perforating roll serves to print a portion of the paper web forming a ticket, and also perforates the paper web between that ticket and the next one. The perforating roll is equipped with toothed plates 78, protruding from its periphery on opposite sides for perforating purposes.

Mounted above the printing roll and fast on a spindle 79 journaled in the frame plates 13 and 62 is an inking roll 80, which engages the printing roll and inks the latter during the ticket printing operation.

Mounted on the spindle 67 of the perforating roll and near the inner extremity thereof is a disk 81 having two V-shaped recesses 82 which coincide as to position with perforating pins 78 of the perforating roll. An arm 83, secured to the U-shaped frame member 38, as shown at 84, extends downwardly, its lower extremity being hook-shaped, as shown at 85, its free end being turned upwardly to engage one of the recesses 82 of the disk 81, when the oscillatory frame and the drum move upwardly under

the influence of the recoil of the spring 45, after the key lever and the retaining lever have been disengaged in the manner heretofore explained. The action of this hook-shaped arm 83 upon the disk 81 serves to prevent the possible travel of the printing and perforating rolls beyond the desired limit to print the number of tickets required by any operation of the machine. This hook-shaped lever also will serve to restore the printing and perforating rolls to their proper position in case they have traveled slightly beyond the required limit, since the recesses 82 are outwardly flared and made considerably larger than the engaging upturned extremity 86 of the hook-shaped arm.

As the printed and perforated portion of the paper web 69 moves rearwardly beyond the rolls 61 and 68, it passes between two cutting jaws 87 and 88, the jaw 87 being lever like and fulcrumed at 89, its short arm being pivotally connected, as shown at 90, with a link 91, whose upper extremity is pivotally connected, as shown at 92, with the U-shaped frame member 38. When the drum and the oscillatory frame upon which it is mounted are at their lowest limit of movement, the link 91 acts to hold the cutting arm 93 of the jaw 87 above the coöperating stationary jaw 88 to allow the printed portion 94 of the paper web to pass between the said jaws. Now, as soon as the key lever and the retaining lever are disengaged and the oscillatory frame and the drum carried thereby move upwardly, the action of the link 91 is such as to move the arm 93 of the jaw 87 downwardly whereby it serves in conjunction with the stationary jaw 88 to cut off the printed portion of the ticket.

At the inner extremity of the spindle 67 is located a toothed wheel 95, which meshes with a gear 96 of a registering or counting device 97, whereby the number of tickets printed by the machine is counted or registered. This registering device, being of the ordinary construction, need not be described in detail.

In order that the drum may act upon the retaining levers 26 at varying intervals of time, the face of the drum is equipped with cams A, B, C, D, and E, lying in different planes and located at varying distances from the retaining levers 26, that lie in the planes of the respective cams, the said distances being measured in a given direction around the drum.

Assuming that the drum is traveling in the direction of the arrow in Fig. 8 and that the key lever having the numeral 1 on its outer extremity is interlocked with the corresponding retaining lever, the cam A will act upon the said interlocked retaining lever after the drum has traveled approximately one-fourth of a revolution, or far enough

to actuate the printing roll sufficiently to print a single ticket. In this explanation, I am assuming that the cams A, B, C, D, and E are arranged in planes to act respectively upon the retaining levers 26, which levers are adapted to respectively interlock with the key levers 9, whose extremities have their push-buttons respectively marked 1, 2, 3, 4 and 5. Hence, the distance of the drum's travel, in order to release any key lever and allow the drum to move upwardly to its normal position, will depend upon which key lever is depressed to interlock engagement with its corresponding retaining lever.

From the foregoing description, the use and operation of my improved machine will be readily understood. It is assumed that the machine is kept in operation during the selling of tickets at an amusement resort or other place where tickets are required in varying numbers by different purchasers.

The motor is set in operation and the operating gears, 52, 55 and 57 only are actuated until a key lever is pressed. When one or more tickets are required, the person in charge of the machine presses a key lever corresponding with the said number. As the key lever is pressed, it moves the drum, together with the oscillatory frame upon which it is mounted, downwardly a sufficient distance to cause its gear 59 to mesh with the operating gear 57 and the gear 65 mounted on the spindle of the printing roll. This sets the drum in operation and simultaneously starts the printing roll, the motion of the drum being continuous for a length of time depending upon the number of tickets required, and, consequently, upon the particular key lever pressed. If the lever having the numeral 1 at its outer extremity is pressed, the drum only remains in operative connection with the operating and printing roll gears long enough to print a single ticket,—consequently, the nearest cam A acts upon its corresponding retaining lever and breaks the interlocking connection between it and its coöperating key lever. However, should five tickets be required, the key lever having the numeral 5 at its outer extremity is pressed, and the drum is held in operative relation with the operating and printing roll gears until the drum has made nearly a revolution, or until the cam E has acted to disengage its corresponding retaining lever from the key lever with which the latter is interlocked. As soon as any retaining lever is disengaged from its corresponding key lever, whereby the drum and its oscillatory frame are allowed to move upwardly, the portion of the paper web 69, which has been printed and perforated, has passed through the opening between the cutting jaws 87 and 88, and, as the frame and drum move upwardly, the jaw 87 is actuated

by the link 91 to cut off the printed and perforated portion of the ticket paper web. Simultaneously with the printing, perforating and cutting operation, the register 97 is actuated whereby the number of tickets printed by the machine is indicated.

From the foregoing description, it will be understood that my improved machine, after the motor is set in operation, is entirely automatic with the single exception that it is necessary for the person in charge to push the required key lever.

In order that the downward movement of any key lever may serve to impart a corresponding downward movement to the drum, the top of the frame member 41 is equipped with a roller 107, with which each key lever is normally in contact, whereby, as any key lever is pressed, it serves to move the oscillating frame, together with the drum carried thereby, in a downward direction, whereby the gear of the drum is brought into operative relation with the operating gear 57 and the gear 65 on the printing roll spindle, as heretofore described.

In order that the person in charge of the machine may have access to the register 97, the rear wall of the casing, directly in front of the register, is provided with an opening 103, normally closed by a small door 104, hinged to the casing at 105 and secured in place by a key-operated lock 106.

Having thus described my invention, what I claim is:

1. In a machine of the class described, the combination of a rotating drum, key levers and coöperating retaining levers, the drum being equipped with cams arranged in the planes of the different retaining levers, the cams being at varying distances from the said levers in the direction of the drum's rotation, and ticket printing mechanism normally out of engagement with the drum, the latter being vertically movable and connected to be depressed into interlocking engagement with the printing mechanism when a key lever is operated, the latter being pivotally mounted, for the purpose set forth.

2. The combination with a suitable frame of a frame mounted to oscillate in the main frame, a drum journaled on the oscillatory frame and equipped with cams arranged at varying distances from an initial point in the direction of the drum's rotation, key levers pivotally mounted, retaining levers arranged to interlock with the key levers when the latter are pressed, the key levers being connected in operative relation with the oscillatory frame, whereby the latter, together with the drum, is moved downwardly by the operation of a key lever, the key levers and retaining levers being arranged to interlock upon the downward movement of a key lever, drum-operating mechanism, and ticket printing mechanism located to engage the drum.

- upon the downward movement of the latter, whereby the drum is operated and in turn operates the ticket printing mechanism, substantially as described.
5. The combination with a suitable frame, of a vertically movable frame mounted therein and normally spring-retained at its upward limit of movement, the said drum being equipped with cams arranged in different planes and at varying distances from an initial point in the direction of the drum's rotation, key levers pivotally mounted and arranged to move the drum downwardly when any lever is operated, retaining levers 10 adapted to interlock with key levers when the latter are operated whereby the drum is held at its downward limit of movement for a predetermined period, the retaining levers being arranged in planes corresponding with 15 the arrangement of the cams on the said drum, drum operating mechanism and ticket printing mechanism located to be connected in operative relation with the drum when the latter is depressed, substantially as described.
- 20 4. The combination with a suitable frame, of spring-held key levers, pivotally mounted thereon, spring-actuated retaining levers arranged to interlock with the respective key levers when the latter are pressed, a drum rotatably mounted in the frame and vertically movable, the drum being normally spring-supported at its upward limit of movement and equipped with cams arranged 25 in planes corresponding with the position of the retaining levers, the drum being also normally spring-retained in an initial position with reference to its rotary travel, drum-operating mechanism, ticket printing 30 mechanism, both of which are arranged to be brought into operative relation with the drum when the latter is depressed, the drum being arranged to be moved downwardly by the operation of any key lever, the drum being held at its downward limit of movement as long as the key lever and retaining lever 35 are in interlocked relation, the cams on the drum being arranged to act upon their respective retaining levers whereby any interlocked retaining lever is actuated to release its coöperating key lever as soon as the proper cam of the drum reaches the interlocked retaining lever, substantially as described.
- 40 5. The combination with a suitable frame, of a drum vertically movable therein and spring-supported at its upward limit of movement, ticket printing and operating mechanism arranged to be connected in operative relation with the drum when the latter is at its downward limit of movement, means for depressing the drum into operative relation with the operating and printing mechanism, and means for maintaining 45 the drum in such operative relation at vary- 50 ing intervals, the said means being automatically unlocked by the movement of the drum, substantially as described.
6. The combination with a suitable frame, of a drum vertically movable therein and normally spring-supported at its upward limit of movement, drum operating and ticket printing mechanism, means arranged to act upon the drum whereby the latter is moved downwardly into operative relation 55 with the drum operating and ticket printing mechanism, means arranged to interlock with the drum depressing means whereby the drum is held in the depressed position during varying intervals of time, the drum being equipped to act upon the retaining means to automatically release the same, substantially as described.
7. The combination with a suitable frame, of a drum vertically movable in the frame, drum operating mechanism and ticket printing and perforating mechanism arranged to be connected in operative relation with the drum when the latter is moved downwardly, levers for depressing the drum, devices arranged to interlock with the drum depressing levers, the drum being equipped to automatically disengage the said interlocking levers from the drum depressing levers, whereby the drum is allowed to move out of operative relation with the drum operating mechanism and the ticket printing and perforating mechanism, substantially as described.
8. The combination with normally inactive ticket printing mechanism, of a drum rotatably mounted, vertically movable and normally spring supported at its upward limit of movement, means for depressing the drum into operative relation with the ticket printing mechanism, means for locking the drum in the adjusted position, means for rotating the drum, and means mounted on the drum for automatically unlocking the locking means at predetermined intervals, substantially as described.
9. The combination with normally inactive ticket printing mechanism, of a drum rotatably mounted, vertically movable and spring supported at its upward limit of movement, means for moving the drum downwardly against the action of the spring into operative relation with the ticket printing mechanism, means for locking the drum in the adjusted position, means for rotating the drum, means mounted on the drum for automatically unlocking the locking means at predetermined intervals, and means for returning the drum rotatably to its initial position.
10. The combination of ticket printing mechanism, a drum rotatably mounted, vertically movable and normally spring supported at its upward limit of movement, means for actuating the drum against the

tension of its spring to bring it into operative relation with the ticket printing mechanism, drum operating mechanism with which the drum is also brought into operative relation when moved downwardly, means for locking the drum at its downward limit of movement, means mounted on the drum for automatically unlocking the locking means at predetermined intervals, means for returning the drum rotatively to its initial position after the said unlocking function has been performed, and means for preventing the drum from traveling beyond the initial position during its reverse rotary movement, substantially as described.

11. The combination with a suitable frame, of a drum vertically movable therein, normally spring supported at its upward limit of movement and mounted to rotate, means for moving the drum downwardly against the action of its spring, ticket printing mechanism with which the drum is brought into operative relation when at its downward limit of movement, drum operating mechanism also connected in operative relation with the drum when in its lowermost position, means for locking the drum in position, when adjusted for operating the ticket printing mechanism, means mounted on the drum for unlocking the locking means at predetermined intervals, a coiled spring acting on the drum to return it rotatively to its initial position, and a locking dog for preventing its reverse rotation beyond such position, substantially as described.

12. The combination with a frame work, of a drum rotatably mounted and bodily movable therein, means for imparting the bodily movement to the drum, means for locking the drum in the adjusted position, means for imparting rotary movement to the drum when in such position, ticket printing mechanism in operative engagement with the drum when in the adjusted position, the drum being equipped to automatically unlock the locking means, substantially as described.

13. The combination with a frame work, of a drum rotatably mounted and bodily movable therein, means for imparting the bodily movement to the drum, means for locking it in the adjusted position, means for imparting rotary movement thereto when in the adjusted position, ticket printing mechanism in operative engagement with the drum when in the last-named position, and means for reversing the rotary action of the drum after each ticket printing act.

14. The combination with a frame work, of a drum rotatably mounted and bodily movable therein, a spring connected with the drum and having a tendency to maintain it normally in a predetermined posi-

tion, means for imparting the bodily movement to the drum against the action of its spring, means for locking it in the adjusted position, means for imparting rotary movement to the drum when in the adjusted position, ticket printing mechanism in operative engagement with the drum when in the last-named position, comprising a ticket printing roll, a coöperating perforating roll, a roll for carrying a paper strip upon which the tickets are printed, means for automatically cutting off the printed part of the strip simultaneously with the return of the drum to its normal position in response to the tension of its spring.

15. The combination of a frame work, a drum bodily movable in the frame work, a spring having a tendency to normally maintain the drum in its initial position, means for imparting the bodily movement to the drum against the action of its spring, means for locking it in the adjusted position, means for imparting rotary movement to the drum when in the adjusted position, ticket printing mechanism in operative engagement with the drum when in the last-named position, comprising a ticket printing roll, a coöperating perforating roll, a roll for carrying a paper strip upon which the tickets are printed, the printing and perforating rolls causing the paper strip to travel between them simultaneously with the ticket printing and perforating operation, and means for automatically cutting off the printed part of the strip, simultaneously with the return of the drum bodily to its normal position, under the influence of its spring.

16. The combination with a frame work, of a drum bodily movable in the frame work, a spring having a tendency to maintain the drum in its normal position, means for actuating the drum bodily against the tension of its spring, means for locking the drum in the adjusted position, means for imparting rotary movement to the drum when in the last-named position, a ticket printing roll, a coöperating perforating roll, a roll for carrying a strip of paper upon which the tickets are printed, the printing and perforating rolls serving to feed the strip of paper, simultaneously with the printing operation, and an inking roll co-operating with the printing roll during the printing operation, substantially as described.

17. The combination of a drum rotatably mounted and bodily movable, a spring having a tendency to normally maintain the drum in its normal position against bodily movement, means for imparting the bodily movement to the drum against the tension of its spring, means for locking the drum in the adjusted position, means for imparting rotary movement thereto when in the last

named position, a ticket printing roll, a co-operating roll, a roll for carrying a paper strip upon which the tickets are printed, the ticket printing and perforating rolls 5 serving to cause the said paper strip to travel between them during the ticket printing and perforating operation, and means for automatically cutting off the printed strip of the roll simultaneously with the re- 10 turn of the drum to its normal position of

bodily movement, said means comprising a stationary cutting jaw and a co-operating movable jaw, substantially as described.

In testimony whereof I affix my signature in presence of two witnesses.

ROY M. RICKERT.
